HOIST SHOVEL

Juan Gutierrez Salido, Central Preston, Cuba

Application April 9, 1951, Serial No. 220,108

2 Claims. (Cl. 37—187)

1

This invention relates to a hoist shovel of the segmental bucket type.

The hoist shovel to which the invention has particular application has utility in the handling of coal, gravel, earth, and like materials normally lifted by crane booms in the loading and discharge of materials of this class in respect to ships, cars and excavating operations.

An object of the invention is to provide a hoist shovel which will be simple and economical in construction and efficient in operation.

Another object is to provide apparatus of the character and for the purposes described which may be readily and economically produced.

Other advantages of the invention will be discernible from the description thereof hereinafter set forth.

The invention is embodied in a hoist shovel exemplified in the accompanying drawings in which the views are as follows, like reference numerals designating like parts throughout the several views:

Fig. 1, a side elevation of the shovel with bucket in closed position and

Fig. 2, the same view with buckets in open position;

Fig. 3, the view shown in the preceding figures with the lifting mechanism in a different stage; and

Fig. 4, a front elevation of the shovel.

According to the invention, the hoist shovel comprises a main frame and a lifting frame slideable therein, a coupling block separate from the lifting frame and engageable therewith, a pair of side plates carried by the main frame and a pair of bucket segments pivoted thereto, means operable by the coupling block to pivot the bucket segments between open and closed positions, latching means connecting the coupling block with the lifting frame to close the buckets upon the upward movement of the lifting frame and releasable to free the coupling block to drop and open the buckets; the side plates are formed to assist the buckets in defining the load receivable therein.

The hoist shovel has a main frame comprising a pair of upright side posts 1 (Fig. 4), braced across the top ends thereof by a cross member 2 and terminating at their bottom ends in a pair of sills 3. The cross member 2 has a projecting flange 4 at each end thereof to form a stop member thereon.

Arranged in the main frame for vertical travel in relation thereto, is a lifting frame having a pair of upright slides 5 on each side thereof.

2

These slides are flanged as at 6 along their side edges to move in complementary grooves (not shown) formed in a pair of spaced-apart guide rails 7 running along the outer faces of the posts 1. Across the top end thereof, the slides 5 are braced by a cross-member 8 to which a lifting ring 9 is fastened to receive a hoisting cable 10.

The main frame (Fig. 2) has arranged in the lower portion thereof, a pair of coupling shoes 11 which are in vertical alignment with the slides thereabove but separable therefrom and these shoes have their side edges flanged in like manner as the slides for vertical travel between the guide rails 7. The shoes 11 carry near their lower ends a pair of outwardly projecting link pins 12 engageable with a pair of links 13 each having a longitudinal slot 14 for reception of the link pin 12 in slidable and pivotable relation therewith. At their outer end, the links 13 are welded or otherwise secured to the upper portions of a pair of segmental complementary buckets 15 (Fig. 2) which are each pivoted upon a shaft 16 extending laterally through each bucket and carried by a pair of side plates 17 secured to the inner faces of the posts 1 with which they may be integrally formed.

It will be seen that when the coupling shoe 11 is moved between its upper position (Fig. 1) and lowermost position (Fig. 2), the links move therewith to pivot the buckets between their closed and open positions. The sills 3 carry a buffer spring 18 to cushion the impact of the shoes 11 descending thereagainst.

The slides 5 have formed near the bottom ends thereof, a pair of blocks 19 moveable therewith. These blocks carry a stop member 20 at their top ends to limit the upward travel of the lifting frame by engagement with the stops 4 (Fig. 1). The lifting frame is thus reciprocable between the limits imposed between the cross-member 8 and stops 4, it being understood that loading conditions of the buckets may impose limits of travel somewhat short of these stops.

Pivots connected to the lifting frame, is a latching frame comprising a pair of hook levers 21 arranged on each side thereof and fulcrumed on a pair of outwardly projecting pivot pins 22 formed on the blocks 19. At their bottom ends, the levers 21 terminate in hooks 23 engageable with a pair of outwardly extending lift lugs 24 carried by the upper portion of the coupling shoes 11 (Fig. 1), to latch these shoes to the lifting frame. Thus, when the shovel is in suspension from the hoist cable with the shoes 11 latched to

the lifting frame, as shown in Fig. 1, the buckets 15 are in their closed positions.

The hook levers 21 are urged into latching relation with the lift lugs 24 by a spring 25 fastened at one end to the backs of the levers and at their opposite ends to the blocks 19. Across their top ends, the hook levers are braced by a cross-piece 26 (Figs. 1 and 4), to which is secured a pulley 27 co-operating with a pulley 28 and hook-eye 29 fastened to the cross-member 8, whereby a pull cord passing through these pulleys may be pulled by an operator in the direction of the arrow (Fig. 1) to disengage the hooks 23 to permit the coupling shoes 11 to descend for the purpose of opening the buckets as illustrated in Fig. 2.

The side plates 17 are shaped at the bottom thereof to form a triangular spade member 30 functioning to assist in the breaking up of hard material handled by the shovel and at the same time confining the material being scooped up thereby. Suitable teeth 31 may be formed along the biting edges of the buckets in a manner well known by those skilled in the art.

In practice, the shovel is impinged upon the material to be handled with buckets open and resting thereon. In this condition, the cable 10 will be slack and the lifting frame will thus descend in the main frame with hooks 23 engaged. On applying hoist to the cable, the lifting frame is raised thereby to elevate the coupling shoes 11 to actuate the links 13 and contract the buckets to close. The loaded shovel is then swung to the discharge point, the operator pulls the cord actuating the latching frame to disengage hooks 23.

The coupling shoes 11, now released from the lifting frame, are freed to descend to the bottom of the posts 1 to thereby actuate the linkage intervening between the shoes 11 and the jaws for the expansion thereof and the discharge of the load therefrom.

The side plates 17 function intermediate the adjacent side walls of the jaws to form therewith a unitary bucket wall confining the load on each side thereof and the spade point 30, forming the bottom terminus of the plates, is adapted to penetrate the material being loaded to thus assist the bottom edge portions of the jaws therein. These plates, further, define the side limits of the load being handled and prevent the spilling of material between the inner edges of the jaw side walls.

The invention thus provides an apparatus of the character herein described meeting the objects hereinabove set forth.

Of course, the invention is susceptible of various modifications without departing from the scope thereof as hereinafter claimed.

Having thus described the invention and the mode of its practice, what I claim as new and desire to secure by Letters Patent of the United States is:

1. In a hoist shovel having a hoist cable, the combination therewith of a lifting frame suspendable therefrom and including a pair of upright slides on each side thereof, a main frame suspendable from said lifting frame and having a pair of upright posts receiving said slides in vertical travel therealong, a pair of sidewise plates carried by said posts and a pair of oscillatory bucket jaws pivoted to said plates, a pair of coupling shoes slidable along said posts, linkage means connecting said jaws with said shoes and actuatable thereby to oscillate said jaws, an oscillatory latching frame carried by said lifting frame and engageable with said shoes to effect the elevation thereof in unitary movement with said lifting frame whereby to contract said jaws, means biasing said latching frame into normal engagement with said shoes, manually operable pull cable means associated with said latching frame for the pivotal retraction thereof against said biasing means to effect the release of said shoes for the descent thereof whereby to expand said jaws, and each of said plates forming an intermediate central wall portion complementing the side walls of the jaws adjacent thereto whereby to define with said jaw side walls a unitary bucket side wall.
2. The invention as defined in claim 1 and; said plates terminating at the bottom thereof in a downwardly directed spade point to penetrate the material loaded by said shovel and define the side limits of the load, buffer means arranged in said posts adjacent the bottom thereof to cushion the impact of said coupling shoes upon the descent thereof.

JUAN GUTIERREZ SALIDO.
